TREILLAGE

Jacob G. Braun, Wilmette, Ill.

Application March 3, 1958, Serial No. 49,887

Term of patent 14 years

(Cl. D54—2)

3ug. 1.

Fig. 1 is a front elevation view of a trellis embodying my new design;

Fig. 2 is a fragmentary enlarged view of portions of the trellis shown in Fig. 1;

Fig. 3 is a sectional view taken along the line 3—3 looking in the direction of the arrows;

Fig. 4 is a sectional view taken along the line 4—4 looking in the direction of the arrows.

The characteristic feature of my design resides in the particular configuration of the artistry within the illustrated framework.

The appearance of the opposite side of the design is the same as that of the face thereof illustrated in Fig. 1.

I claim:

The ornamental design for a trellis, substantially as shown and described.
